UNITED STATES PATENT OFFICE.

THOMAS SMART, OF PORT MOODY, BRITISH COLUMBIA, CANADA.

RAIL STOP.

Application filed May 2, 1928. Serial No. 274,620.

My invention relates to improvements in rail stops which are particularly adapted for use in dry kilns of lumber mills and other like situations where the rails are usually 5 laid on a slight incline, so that the cars may travel by gravity from one point to another. The object of the invention is to provide a stop which may be readily collapsed and removed from the rail and as quickly reassembled in position to prevent the passage of further rolling stock.

The invention consists essentially of a pair of arms pivotally connected to one rail of the track of which one is provided with a 15 stop capable of being disposed transversely of said track and means for releasably connecting the free ends of said arms together, as will be more fully described in the following specification, and shown in the accompanying drawings in which:—

Fig. 1 is an elevation of the invention fitted to a rail.

Fig. 2 is a plan view.

In the drawings like characters of reference indicate corresponding parts in each figure.

The numeral 1 indicates one of the rails of a tramway track along which a car 2 is adapted to travel. The car 2 such as is used 30 in lumber kilns and the like, is provided with a low built frame 3 having transverse members 4 at opposite ends. The frame 3 is mounted upon small flanged wheels 5. An eye bolt 6 extends freely through the web 35 of the rail 1 which is provided with a shoulder 7 adjacent one end so as to project the eye 8 of the bolt a suitable distance beyond the bulb of the rail 1. The opposite end of the bolt 6 is fitted with a distance collar 9 and a pair of lock nuts 10.

Hingedly connected to the eye 8 of the bolt 6 as at 11 is an upturned L-shaped arm 12 having a vertical member 13 from which a transverse portion forming an abutment 14 extends, the free end of the abutment being outwardly turned as at 15 in a plane parallel to the upturned portion 13. Aligned apertures 16 are formed in the portions 13 and 15, the purpose of which will hereinafter appear. Pivots mounted upon the bolt 6 between the distance collar 9 and the lock nuts 10 is a further L-shaped arm 17 having an upturned end portion 18 which is apertured as at 19 to register with the apertures 16. A withdrawable pin 20 is normally carried in the apertures 16 and 19 for the pur-

pose of supporting the arm 17 in a position parallel to the arm 12 and for anchoring the end portion 15 of the abutment back to the bolt 6 through the arm 17. This pin is 60 preferably provided with a chain 21 secured at one end to the arm 12.

Having thus described the several parts of my invention I will now briefly explain its use.

The rail stop is set up in position as shown with the abutment 14 lying transversely across the rail 1 and the pin 20 inserted through the apertures 16 and 19 so that all the several parts are firmly connected together to withstand the shock of a car being brought to rest with its transverse end member 4 in contact with the abutment 14. It will be readily assumed that where the track is set on an incline and a loaded car is held 75 against movement by the rail stop that an appreciable strain would be imposed upon the stop, this strain is mainly applied through the arm 12 to one end of the eye bolt 6 and through the end of the pin 20 and the 80 arm 17 to the other end, therefore by simply snatching the pin 20 by the chain or by driving it with a light hammer blow, it is withdrawn from the aperture 19 in the upturned end 18 of the arm 17 which falls by gravity 85 below the top of the rail as shown in dotted line in Figure 1, and the arm 12 with its abutment 14 is swung clear of the car 2, see position indicated by dotted line in Figure 2, and the car is free to move further down the 90 inclined track as desired. It will be apparent that as soon as the abutment 14 is moved beyond the edge of the rail, the arm 12 is permitted to drop also, so as to be free of any overhanging projections of the car which 95 might otherwise obstruct the passage of the car along the track.

What I claim as my invention is:

1. The combination with a track rail, of a stop comprising a pair of L-shaped arms 100 each having a horizontal member pivotally connected at one end to the rail and an upturned member at the other, and means for releasably connecting the upturned members together across the rail.

2. The combination with a track rail, of a stop comprising a pair of L-shaped arms 110 each having a horizontal member pivotally connected at one end to the rail and an upturned member at the other, and a pin for releasably connecting the upturned members together across the rail.

3. The combination with a track rail, of a stop comprising a pair of L-shaped arms each having a horizontal member pivotally connected at one end to the rail and an upturned member at the other, an abutment carried by one of the upturned members, and means for releasably connecting said upturned members together with the abutment interposed therebetween.
- 5 4. The combination with a track rail, of a stop comprising a pair of L-shaped arms each having a horizontal member pivotally

connected at one end to the rail and an upturned member at the other, an abutment carried by one of the upturned members, and means for releasably connecting said upturned members together with the abutment interposed therebetween, the pivotal connection of one of said arms permitting a movement of said arm in vertical and horizontal directions.

Dated at Vancouver, B. C., this 23rd day of April, 1928.

THOMAS SMART.
